United States Patent Office

Des. 228,772
Patented Oct. 23, 1973

228,772

PUZZLE

Alan A. Hicks, Weston, Conn., assignor to Kohner Bros., Inc., East Paterson, N.J.

Filed Dec. 13, 1971, Ser. No. 207,715

Term of patent 14 years

Int. Cl. D21—01

U.S. Cl. D34—15 M

FIG. 1

FIG. 2

FIG. 3

FIG. 4

FIG. 5

FIG. 6

FIG. 1 is a perspective view of a puzzle embodying my new design and showing movable spheres in the channels;

FIG. 2 is a bottom plan view thereof;

FIG. 3 is a rear elevational view of FIG. 2 wherein the upper portion is the bottom;

FIG. 4 is a top plan view thereof including the movable spheres;

FIG. 5 is a side elevational view thereof; and

FIG. 6 is a front elevational view thereof.

I claim:

The ornamental design for a puzzle, as shown.
